UNITED STATES PATENT OFFICE.

VINCENT G. APPLE, OF DAYTON, OHIO, AND WILLIAM M. S. MILLER, OF MILWAUKEE, WISCONSIN; SAID MILLER ASSIGNEE TO THE APPLE ELECTRIC COMPANY, OF DAYTON, OHIO.

SWITCH.

1,158,955.

Specification of Letters Patent. Patented Nov. 2, 1915.

Application filed November 19, 1914. Serial No. 872,933.

To all whom it may concern:

Be it known that we, VINCENT G. APPLE and WILLIAM M. S. MILLER, citizens of the United States, residing, respectively, at 5 Dayton, in the county of Montgomery and State of Ohio, and at Milwaukee, in the county of Milwaukee and State of Wisconsin, have invented certain new and useful Improvements in Switches, of which the 10 following is a specification.

This invention relates to improvements in switches and more particularly to a switch adapted for use in gas engine electric motor-generator starting systems.

15 One of the objects of our invention is to provide a switch of rugged, sturdy and simple construction inclosed in a weather proof casing and operable through the medium of a reciprocable plunger.

20 Another object is the provision of a switch having eight contact points, four of which are normally in engagement with a pair of switch blades and the other four of which are engaged by the blades when 25 the plunger is depressed.

Still a further object of our invention is the simplification of switches of the type having their movable switch members resiliently connected to the actuating part 30 thus insuring quick, snappy breaking and making of the electrical connections.

Other and further objects will become apparent to those skilled in the art from a consideration of the following description 35 and drawings, wherein—

Figure 1 is a front elevation of our improved switch with the casing cover removed. Fig. 2 is a side elevation. Fig. 3 is a vertical, sectional view on the line 3—3 40 of Fig. 2. Fig. 4 is a horizontal, fragmentary sectional view on the line 4—4 of Fig. 3.

In general the structure comprises an inclosing casing 10 within which is reciprocably mounted a plunger 11 to which is resiliently connected a pair of V-shaped switch blades 12 and 13, adapted to make contact when in their normal uppermost position with fingers 14, 15, 16 and 17 and 45 when the plunger is depressed making engagement with contacts 18, 19, 20 and 21.

The switch blades are slidable on the actuating plunger and resiliently connected thereto by means of two opposing springs 50 secured to the plunger above and below the

blades. To insure a quick, snappy making and breaking of the connection we have provided a latch device that holds the blades in their previously assumed position until one or the other of the springs above referred to 60 has been considerably compressed, when the latch will release and permit the compressed spring to throw the blades from one position to the other with a quick, positive movement.

More specifically the casing 10 comprises a rectangular back section or wall 22 having perforations 23 at its upper corners and perforated lugs 24 projecting from its side to provide means for securing the apparatus 70 to the frame 25 or other suitable parts of a motor vehicle.

Projecting from the back piece 22 is a bottom wall 26, side walls 27—27 and an arcuate top wall 28 forming a box like 75 structure over the opening of which is positioned a removable cover 29 secured to the walls of the casing by means of screws 30.

The vertically reciprocable rod 11 passes through the walls 28 and 26 of the casing 80 and is normally held in its uppermost position by means of the relatively stiff spring 31 bearing at its lower end on the outer face of the wall 28 and at its upper end upon the nut 32 screw threaded upon the upper 85 portion of the plunger. A foot pedal, or button 33, is mounted on the extreme upper end of the plunger 11, and the casing is so mounted as to project this button through either the dash board, or the foot board of 90 the vehicle at a suitable place easily reached by the operator's foot.

A thimble 34 having a downwardly extending reduced tubular part 35 projecting from its lower end surrounds the plunger 95 11 within the casing. The upper enlarged portion of the thimble is bored out at 36 to a diameter greater than that of its plunger so as to receive a coil spring 37, the purpose of which we will later describe. The tubular extension 35 makes a sliding fit with the plunger.

The two V-shaped switch blades 12 and 13 are provided at their inwardly projecting ends with horizontal sections perforated to 105 receive the tubular part 35 and are secured thereon by means of the nut 38 screw threaded upon the extreme lower end of the tube. The blades are electrically insulated from each other as well as from the tubes 35, the 110

thimble 34 and the nut 38, by means of the fiber washers 39 and bushings 40. The thimble 34 is provided at its opposite sides with an upper and a lower pair of grooves 41, 42, alternately engaged by the spring pressed balls 43-43. The front and rear faces of the thimble are cut away on parallel planes, the rear face making sliding contact with the base wall 22. Oppositely positioned tubular projections 44-44 extend inwardly from the vertical walls 27 of the casing and contain the balls 43-43 together with their coil springs 45-45. The resilient pressure of the spring pressed balls 43-43 against a pair of the grooves, as for example grooves 42-42 of the thimble 34, resists movement of the thimble until the pressure exerted thereon overcomes the pressure exerted by the pair of springs 45-45 and permits the wedging of the balls out of the path of the ridges 41'-41' lying between the pair of grooves 41-41 and 42-42.

The lower end of the spring 37 fits within the opening 36 in the upper end of the thimble and at its upper end bears against the washer 46 secured from vertical movement on the plunger by means of a cotter pin 47. A similar plunger encircling spring 48 pressed upwardly against the lower end of the thimble, engages the end of the tubular portion 35, its lower end pressing against a washer 49 secured from downward movement on the plunger 11 by means of the cotter pin 50. From so much of the description it will be evident that the box switch blade-carrying thimble is slidable upon the operating plunger 11, its movement in either direction being communicated to it from the plunger through one or the other of the coil springs 37-48.

When in the position illustrated in Fig. 1, the spring pressed balls 43-43 hold the thimble and switch blades in their uppermost position. Downward pressure upon the plunger compresses the spring 37 until its force is sufficient to overcome the side pressure of the springs 45-45 and wedge the balls 43-43 out of the grooves 42-42, permitting the stored energy of the spring 36 to quickly throw the thimble together with the blades downward until the balls 43-43 engage with the upper set of grooves 41-41. On the reverse movement of the plunger the spring 48 is compressed until its force is sufficient to overcome the horizontal thrust of the spring pressed balls 43-43 against the ridges 41'-41'.

As the contacts 18-19 and 20-21 carry the heavy current required for starting the engine we have formed each of these from a plurality of metallic strips secured at their lower ends in L-shaped holders 18'-19' and 20'-21'. Binding posts 51, 52 extend outwardly from the vertical legs of the holders 18'-21' through the walls 27-27 of the

casing, being insulated therefrom by the fiber washers 53 and bushings 54. The holders 18'-19' and 20'-21' are insulated from the inner surfaces of the casing walls by means of the fiber strips 55-55 extending up the vertical walls 27-27 and the horizontal strips 56-56 lying on the bottom wall of the casing 26 and extending inwardly to a point where they contact with the fiber block 57.

The holders 19' and 20' are provided with vertically, downwardly extending binding posts 58, 59 electrically insulated from the casing by the fiber washers 60 and bushings 61. The upper adjacent ends of the pairs of contacts 18-19 and 20-21 are beveled off to engage the outer edges of the V-shaped blades 12 and 13.

At the upper corner of the right hand wall 27 below the tubular projection 44 a binding post 62 extends through the wall carrying at its inner end a screw head 63 overlying the strip 64, the upper end of which is hooked inwardly and downwardly to form the contact finger 17. Parallel with the strip 64 and insulated therefrom by a fiber strip 65, is a second strip 66, the upper end of which terminates in the contact finger 16, positioned beside contact finger 17. The lower end of the strip 66 extends downwardly the length of the wall 27 and into engagement with the binding post 52 at its base where it joins the contact holder 21'. By this construction contact 17 is electrically connected with binding post 62 whereas contact 16 is electrically connected with contact 21 and binding post 52. At the opposite side wall of the casing a similar binding post 67 extends through the casing and carries at its inner end the strip 68 on the upper end of which is formed the contact finger 15. The contact 14 as at the opposite side of the casing terminate in a vertically extending strip 69 connected at its lower end with the binding post 51 at the point where it joins the contact holder 18'. An insulated metallic strip 70 extends diagonally across the back wall 22 of the casing being connected at its upper end with contact strip 68 and at its lower end with the binding post 59.

When in its uppermost normal position the switch blade 12 electrically connects the contacts 14 and 15, the blade 13 connecting contacts 16 and 17. When pressed downward against the action of the spring 31 the switch blade 12 makes electrical connection between the contacts 18 and 19, whereas the blade 13 electrically connects the contacts 20 and 21.

Electrically, the connections made by the switch blade when in its normal up position, the contacts 14 and 15 being bridged, connect terminal 67 with both terminals 51 and 59, the former through strip 69 and the lat-

ter through strip 70 whereas the bridging of contacts 16 and 17 connects terminals 62 and 52 through strip 66. When the pedal is pushed down to starting position the terminals 51 and 58 are connected through blade 12 and terminals 52 and 59 are connected through blade 13.

Having described our invention, what we claim is:—

10 1. In an electric switch the combination of an actuating member, a movable switch member slideable thereon, a resilient connection between said switch member and the actuating member, contacts engaged by said 15 switch member when in one extreme position, contacts engaged by said switch member when in its opposite extreme position, said members having a pair of grooves formed therein, one above the other, and a 20 spring pressed latch adapted to engage one or the other of said grooves when the switch member is in one or the other of its extreme positions.

2. In an electric switch the combination 25 of a casing, a plunger axially slideable through said casing, a thimble slidably mounted on said plunger and movable into one or the other of two positions, V-shaped switch blades carried by said thimble, contacts positioned in the upper portion of said 30 casing and adapted to engage the outermost legs of said V-shaped switch blades when in one extreme position, two pairs of contacts positioned in the lower portion of said casing 35 each pair being adapted to engage the outer surfaces of the two legs of the V-

shaped switch blades when in the other extreme position, a resilient connection between said thimble and plunger and a latch for holding the said thimble in its last assumed position until the plunger has reached the end of its stroke in either direction.

3. In an electric switch the combination of a casing, a plunger axially slideable 45 through said casing, a member slidably mounted on said plunger and movable into one or the other of two positions, a pair of switch blades carried by said member, contacts positioned in the upper portion of said casing and adapted to engage the said blades when in one extreme position, two pairs of contacts positioned in the lower portion of the casing, each pair being adapted to be engaged by one of the blades when 50 in the other extreme position, a resilient connection between said member and plunger and a latch for holding the said member in its last assumed position until the plunger has reached the end of its stroke in 55 either direction.

In testimony whereof we hereunto set our hands.

VINCENT G. APPLE.
